(57) **CLAIM**

The ornamental design for a multi-purpose bicycle tool, as shown and described.

DESCRIPTION

FIG. 1 is a left, rear perspective view of a multi-purpose bicycle tool in a closed position according to our novel design;

FIG. 2 is a rear side view of the multi-purpose bicycle tool in a closed position according to our novel design;

FIG. 3 is a front side view of the multi-purpose bicycle tool in a closed position according to our novel design;

FIG. 4 is a bottom view of the multi-purpose bicycle tool in a closed position according to our novel design;

FIG. 5 is a top view of the multi-purpose bicycle tool in a closed position according to our novel design; and

FIG. 6 is a right end view of the multi-purpose bicycle tool in a closed position according to our novel design.

FIG. 7 is a left end view of the multi-purpose bicycle tool in a closed position according to our novel design; and,

FIG. 8 is a left, rear perspective view of the multi-purpose bicycle tool in an open position according to our novel design.

The broken lines are for illustrative purposes only and form no part of the claimed design.
